MOLD FOR JACKETING VASE RECEPTACLES
Frank Jacomaro, 1855 Narragansett, Chicago 39, Ill.
Filed Aug. 1, 1958, Ser. No. 752,644
4 Claims. (Cl. 25—118)

The present invention generally relates to a mold for jacketing a receptacle for a vase.

There is presently provided a generally cylindrical receptacle having a flange at the upper end thereof which is embedded in the ground surface with the receptacle having means for supporting a vase with the vase protruding above the receptacle or disposed in inverted relation with the vase inserted into the receptacle. These devices are normally employed in cemeteries for receiving cut flowers or the like with the construction of the vase being such that when the vase is inverted and inserted into the receptacle, the entire mechanism is generally flush with the ground surface so that the grass may be easily mowed. When the ground is soft which frequently occurs from the rain and people happen to step on the flange or if machinery or mowers are run on the flanges or receptacles, there is quite often a tendency of the receptacle to tilt which causes one edge thereof to protrude above the surface of the ground which constitutes a hazard because some person may stumble or fall and such protrusion may cause damage to mowers or the like that pass over the vase assembly and will also damage the vase. Therefore, it is the primary object of the present invention to provide a mold for forming a jacket over the cylindrical receptacle with the jacket being constructed of concrete or similar material which is tapered from a one-inch thickness at the top to three inches at the bottom thus providing a generally frusto-conical shape in which the bottom provides a footing to help maintain the vase receptacle in a level condition and also to prevent any possibility of the device being pulled out or tilted while in position.

Another important feature of the present invention is to provide a mold for jacketing a cylindrical receptacle which is simple in construction, easy to use, and relatively inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the jacketed receptacle and vase formed by using the mold of the present invention installed in flush relation to the ground surface;

FIGURE 2 is a sectional view through the receptacle, the mold and the jacket contained by the mold;

FIGURE 3 is a bottom plan view of the construction of FIGURE 2;

FIGURE 4 is a detailed sectional view showing the bayonet slot construction for attaching the vase to the receptacle;

FIGURE 5 is an exploded group perspective view showing the mold and receptacle and interconnecting mechanism; and

FIGURE 6 is a vertical sectional view taken substantially upon a plane passing along section line 6—6 of FIGURE 1 illustrating the relationship of the jacketed receptacle and vase.

Referring now specifically to the drawings, the numeral 10 generally designates the jacketed vase receptacle while the numeral 12 generally designates the mold of the present invention for jacketing the receptacle.

2

The conventional cylindrical receptacle is designated by the numeral 14 and includes a peripheral flange 16 at its upper end thereof which includes a plurality of bayonet type slots or notches 18 formed therein for receiving 5 projecting lugs 20 on a cylindrical vase 22 having a bottom 24 and handle forming lugs 26. The bottom 24 is preferably concave on its lower surface with the lug 26 having an upper edge generally in the same plane as the flange 16 when the vase 22 is inverted and inserted 10 into the cylindrical receptacle 14 thus providing a generally smooth surface with the surrounding ground area designated by the numeral 28.

As shown in FIGURE 6, there is provided an encircling jacket or casing 30 of concrete or other suitable 15 material which completely encircles and encloses the cylindrical receptacle 14 and which has a greater thickness at the bottom than at the top thus defining with the receptacle 14 a generally frusto-conical member having an upper surface generally contiguous with the surface 20 of the surrounding ground area and generally providing no obstructions to movement of a lawn mower or similar machinery over the ground surface when the vase is inverted and inserted into the receptacle 14. The relatively enlarged lower end of the jacket 30 provides a 25 footing for the entire assembly and generally prevents tilting of the same due to its engagement with the surrounding earth whereby the shape of the device prevents upward movement thereof and prevents tilting thereof.

Referring now specifically to FIGURES 2 and 5, the 30 mold 12 generally includes a peripheral wall 32 defining a frusto-conical shape and having an inwardly extending bottom member 34 at the lower end thereof having an opening 36 receiving the flange 16 on the receptacle 14 wherein the flange and the bottom 34 form a 35 bottom for the mold whereas the cylindrical receptacle 14 and the peripheral wall 32 provide spaced walls for receiving the concrete jacket 30 so that the concrete jacket 30 will be shaped and formed into the desired frusto-conical shape so that the same may be inverted with the 40 thicker or larger end forming the lower end of the jacket 30.

For holding the cylindrical receptacle 14 in rigid relation to the bottom wall 34, the bottom wall 34 is provided with a peripheral plate 38 secured to the outer surface thereof and engaging the outer surface of the flange 16 for limiting the insertion thereof. Inserted into the open end of the receptacle 14 is a first plate 40 having a plurality of projecting lugs 42 thereon which engage with the bayonet slots 18 in the receptacle 14 for mounting the first plate 40 detachably therein. The first plate 40 is 45 also provided with a centrally disposed threaded stud 44 welded thereto or otherwise rigidly secured thereto which receives a wing nut 46 thereon. Clampingly disposed under the wing nut is a second plate 48 of circular construction having a central aperture 50 receiving the threaded stud 44 with the second plate 48 resting against the outer surface of the peripheral plate 38 welded to the bottom member 34. Thus by tightening the wing nut 46, the receptacle 14 is rigidly secured to the bottom member 34 and will be maintained in that position while the concrete 55 30 sets up after which the second plate 48, first plate 40 and mold 12 may be removed and the assembly inverted and placed in the ground 28 in the desired manner which provides for concealment of the vase and provides concrete support for the vase so that the same will be 60 maintained in the desired vertical condition and preventing the possible tilting of the vase assembly due to machinery or persons stepping on the same.

It is pointed out that various minor changes may be 65 adapted in the mold for employment of the device with various commercially available vase and receptacle assemblies with most of these changes being in the particu-

lar size and construction of the plate having the lugs thereon in order to anchor the top of the mold in secure position with the top of the mold actually being the bottom 34 when the concrete is poured into the mold and the mold may be constructed of any suitable material such as sheet metal or the like.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A portable device for combining a receptacle with a jacket of concrete, said receptacle having a peripheral flange at one end thereof comprising, a mold having a peripheral inclined wall, an open top and an inwardly extending bottom member provided with a central opening for receiving the flange on the end of the receptacle, a peripheral plate attached to the outer surface of the bottom member and extending inwardly past the edge of the opening for forming an abutment for the flange on the receptacle, said bottom member having a thickness substantially equal to the flange whereby the flange will project above the surface of the jacket, a first plate adapted to be detachably connected to the receptacle, a second plate engaging the outer surface of the peripheral plate, and means interconnecting said plates for pulling the first and second plates towards each other for retaining the receptacle and receptacle flange in rigid engagement with the peripheral plate mounted on the bottom member thereby rigidly securing the receptacle to the bottom member in sealed relation for receiving a filler of concrete between the receptacle and the wall of the open topped mold.

2. The structure as defined in claim 1 wherein said bottom forming member is concave on the inner surface thereby providing a convex surface to the concrete.

3. An assembly for molding a concrete jacket around a cylindrical container in which the cylindrical container becomes permanently connected with the concrete jacket comprising a tapered peripheral wall of circular cross-sectional configuration, a bottom member on the small end of the wall, said bottom member and wall being of unitary construction, said bottom member having a centrally disposed opening, an annular peripheral plate

mounted on the external surface of the bottom member and having the inner edge thereof disposed inwardly of the periphery of the opening in the bottom member thereby defining an annular recess, the container having a peripheral flange at one end thereof for reception in the recess, the thickness of the bottom member being substantially equal to the thickness of the flange on the container whereby the concrete will be disposed against the top surface of the flange on the container when formed in the mold and disposed below the edge of the flange on the container when the container and jacket are inverted to their utilitarian position, a first plate disposed within the interior of the container, means detachably connecting the first plate to the container, a second plate disposed against the outer surface of the annular peripheral plate and disposed generally in parallel relation to the first plate, a clamp bolt rigid with the first plate and extending through the second plate, said bolt receiving a clamping nut for urging the plates towards each other thereby rigidly securing the container to the bottom member and in rigid relation to the peripheral wall whereby the container forms the core for the mold, said container having a diameter approximately equal to one-half the diameter of the mold at the small end thereof for providing a substantial thickness to the jacket at the small upper end of the jacket and container assembly when disposed with the flange in the uppermost position.

4. The structure as defined in claim 3 wherein the bottom member is concavely curved whereby a convex top surface will be formed on the jacket peripherally of the flange on the container thereby forming a self-drainage device to prevent entry of water into the container and also providing a smooth upward projection in the soil surface in which the container and jacket are disposed.
